Application May 27, 1949, Serial No. 95,807

9 Claims. (Cl. 318—269)

1

This invention relates to electrically actuated propelling and controlling means for self propelled traction apparatus such as travelling overhead cranes and it resides in an improved form of such apparatus in which novel driving and braking means operate in such manner as to cause the travelling movement to be arrested without hazardous or undesirable mechanical shock, said result being accomplished through the use of induced current or eddy-current torque resisting means, mounted in driven relationship to the propelling mechanism, the same being energized so as to become active to restrain motion, only when an operator actuates a controller from a higher speed driving position to a position calling for deceleration.

One object of this invention is to provide a propelling and controlling apparatus which will permit motion to be smoothly terminated without dependence upon manually operated brakes.

Another object of this invention is to provide propelling and controlling means for the bridge of an electrically driven travelling overhead crane wherein motion is arrested smoothly by means which may be controlled from a point located in a travelling operator's cab attached to the crane trolley.

Another object of this invention is to provide a propelling and controlling apparatus for the bridge of an electrically driven overhead crane which will safely and smoothly arrest motion of the crane in the event of power failure.

Another object of this invention is to provide a propelling and controlling apparatus for the bridge of an electrically driven overhead crane which will make practical increased rates of travel of the bridge of the crane in spite of the use of a trolley mounted operator's cab, without hazard to the operator due to excessive mechanical shock during stopping.

The foregoing and other objects and advantages of this invention are explained in the description which follows, which description is set forth with reference to the accompanying drawings forming a part hereof, in which there is shown, for purposes of illustration and not of limitation, one form in which the apparatus of this invention may be embodied.

In the drawing, Fig. 1 is an electrical circuit diagram of one form of the apparatus of this invention,

Fig. 2 is an end view in elevation diagrammatically depicting one form of crane with which the circuit set forth in Fig. 1 may be employed, and

2

Fig. 3 is a diagrammatic side view in elevation of the crane shown in Fig. 2.

For the driving of overhead cranes and other traction devices it is desirable at times to employ alternating current driven electrical equipment. The usual wound rotor induction motor, having control means for reversing the same and regulating the speed thereof, used for this purpose is subject to certain limitations, one being the fact that such a motor is ill adapted to perform a braking function. Consequently such arrangements have usually depended upon friction service brakes, which are manually applied to produce the desired gradual deceleration prior to the sudden stoppage produced by the usual electro-magnetically released, normally applied, friction holding brakes which become applied whenever power supplied to the motor is interrupted. This arrangement, however, has been suitable only in cranes or other devices having the operator's cab so mounted as to make feasible the necessary mechanical or hydraulic connections between the operator's cab and the service brakes.

In certain instances, it is necessary that the operator's cab be movable in relation to the traction device per se, as is the case where the cab is attached to the trolley of an overhead crane, so as to move lengthwise of the bridge of the crane to permit the operator to maintain a position approximately above the load being lifted. Such cranes are particularly useful where special grapples are employed enabling the operator to engage and release a load without assistance of a ground crew, as for example in the case of lumber cranes. Trolley mounted cabs are also of use in foundry cranes where pouring from a moving ladle is desired and also to a smaller extent in cranes employing clam shells, magnets or other devices which load without the attention of a ground crew. Heretofore in cranes having trolley mounted operator's cabs, because of the difficulty of connecting up manually actuated service brakes, stopping of bridge travel has usually been made to depend upon the so-called holding brake which becomes applied upon discontinuance of power supplied to the propelling motor. The sudden stopping produced by the holding brake, particularly when applied while the bridge is drifting at a rapid rate, causes serious mechanical shocks. As a result it has been customary to limit the rate of travel of the bridge of such cranes to speeds which are but a minor fraction of bridge-travel speeds otherwise considered suitable. Unless this precau-

tion is observed the mechanical shocks are sufficiently severe to subject the entire structure to conditions endangering its structural soundness and to throw the operator about in his control cab with such violence as to make injury likely.

Through the use of the improved apparatus of this invention it is possible to provide alternating current driven traction devices such as overhead cranes in which the rate of travel can be greatly increased without hazardous or undesirable shocks during stopping and without dependence upon manually actuated service brakes.

The apparatus of this invention is suitable for use in connection with a wide range of electrically driven self-propelled apparatus and particularly in connection with cranes of the general type diagrammatically depicted in Figs. 2 and 3. The crane there shown includes a traction device in the form of a horizontal bridge 1 mounted upon end trucks 2 and 3 which in turn are carried for horizontal rolling movement upon runways 4 and 5. Mounted for horizontal transverse movement across the top of bridge 1 is a trolley 6 from which hoisting lines 7 and 8 extend downwardly as shown. Secured to the trolley 6, through extensions 9 of the trolley frame, is an operator's cab 10.

The propelling apparatus causing motion of the bridge 1 upon the runways 4 and 5 comprises, as shown more clearly in Fig. 3, a propelling motor 11 to which a normally applied holding brake 12 is secured and from which an output shaft 13 extends. Also forming a part of the propelling apparatus is a reduction gearing 14 connected in driven relationship to the shaft 13. From the reduction gearing 14, cross shafts 15 and 16 extend to and drivingly join with the trucks 2 and 3 at the ends of the bridge.

In accordance with this invention there is associated in torque resisting relationship to the driving train of the bridge 1, an eddy-current or induced-current brake 17 which is mounted in the instance shown on an extension of shaft 13. The induced-current brake 17 is of well known form, comprising stationary and rotating magnetic members with windings which may be energized to establish a magnetic field mutual to the two members which field gives rise to torque-resisting, induced currents when relative rotation between the two members takes place. Since the details of induced-current or eddy-current brakes (with and without conductor bars) are well known and form no part of this invention the same are not shown herein otherwise than diagrammatically and the term "induced-current brake" is used herein as descriptive of the general class of such devices.

As shown more clearly in Fig. 1, the primary supply leads 18, 19 and 20 of motor 11 are joined with trolley conductors 21, 22 and 23 mounted upon the bridge 1, but not there shown. Extending from the operator's cab 10 in sliding electrical contact with conductors 21, 22 and 23 are primary supply connections 24, 25 and 26 which join as shown with main reversing contactors 27 and 28. The reversing contactors 27 and 28 are connected in turn through appropriate leads with power supply mains 29, 30 and 31. Mains 29, 30 and 31 in turn receive power from trolley conductors 32, 33 and 34 attached to bridge 1.

The admission and regulation of power supplied to motor 11 is arranged to be controlled by a drum or other suitable type of controller designated generally by the numeral 35. Controller

35, in the particular instance shown, is provided with an off position and five forward and five reverse positions.

First forward position of controller

Upon movement of controller 35, shown in off position in Fig. 1, to the first forward position, segments 36 and 37 engage their respective stationary contacts which are joined by leads 38, 39 and 40 with power main 31, thus establishing a control-current supply connection for all of the segments of controller 35. At the same time segment 41 of controller 35 makes contact with its respective stationary contact and thus through lead 42 provides a circuit which joins with winding 43 of contactor 28. The opposite terminal of winding 43 is joined in turn through lead 44, inter-locking contacts 45, and leads 46, 47 and 48 with supply main 29. Contactor 28 is thus caused to close, establishing current supply to the primary of motor 11 for forward driving of the same. The secondary of motor 11 is joined through leads 49, 50 and 51 with trolley conductors 52, 53 and 54, and thence by sliding contact leads 55, 56 and 57, with a resistance grid, generally designated by the numeral 58. Under this condition the full resistance of the grid 58 is included in the secondary circuit of the motor 11 and forward driving at the lowest speed of motor 1 takes place.

Upon closure of main contactor 28, closure of auxiliary contacts 59 provides a connection from supply main 31 through lead 40, lead 60 and lead 61 with lead 62 which joins in turn with the winding of lock-in relay 64. The other end of the winding of relay 64 is joined in turn through lead 65 with lead 41 and thus through lead 48 with supply main 29. The lock-in relay 64 is thus caused to close for a purpose hereafter described.

Movement of the controller 35 from "off" to the first forward position also brings segments 66, 67 and 68 into engagement with their respective stationary contacts but these engagements are temporarily without effect for reasons which will be more fully explained.

In order that motor 11 be permitted to freely rotate with the controller in the first forward position it is necessary that holding brake 12 be released and provision for such release is made through holding brake windings 69 and 70. The windings 69 and 70 are joined by a common lead 71 with one output terminal of rectifier 72 and by leads 73 and 74, which extend through the contacts of normally open holding brake relay 75 and lead 76 to the opposite output terminal of rectifier 72. The rectifier 72 is supplied with alternating current whenever the primary of motor 11 is energized through leads 77 and 78 which extend to primary leads 19 and 20 of motor 11. Leads 77 and 78 also serve to energize the winding of holding brake relay 75. Thus whenever the primary of motor 11 is energized holding brake relay 75 is caused to close and the output of rectifier 72 is applied to the windings 69 and 70 to release the brake 12.

Second forward position of controller

Upon movement of controller 35 from its first into its second forward position segment 79 comes into engagement with its respective stationary contact thus extending a control current circuit through lead 80, the previously closed contacts of lock-in relay 64 and lead 81 to the winding of a second step contactor 82, the opposite terminal of which winding is joined by lead 48 with

supply main 29. This causes contactor 82 to close reducing the amount of resistance of grid 58 which is included in the secondary circuit of motor 11. Motor 11 is thus caused to rotate with increased speed.

Closure of contactor 82 also brings about closure of auxiliary lock-in contacts 83 which prepares a circuit to be subsequently utilized.

Third forward position of controller

Upon movement of controller 35 from its second into its third forward position segment 84 is brought into engagement with its respective stationary contact establishing a current control circuit extending from lead 40 through lead 85, auxiliary lock-in contact 83 and lead 86 to one terminal of the winding of a third step contactor 87. The opposite terminal of the winding of the third step contactor 87 is joined by lead 88 with lead 48 thus completing a circuit which causes third step contactor 87 to close, thus further reducing the amount of resistance of grid 58 which is included in the secondary circuit of motor 11. At the same time auxiliary lock-in contacts 89 are caused to close thus preparing a circuit to be subsequently utilized.

Movement of the controller 35 into the third position also brings segment 90 into engagement with its respective stationary contact thus extending a control circuit through lead 91 to one terminal of the winding of a decelerating relay 92 the opposite terminal of which winding is joined by lead 93 with the lead 48. The relay 92 is thus caused to close for the purpose of preparing certain circuits to be subsequently utilized. In closing, relay 92 establishes for itself a maintaining circuit extending from lead 40 through segment 66, its respective stationary contact, lead 94, and maintaining contacts 95 to lead 96. This maintaining circuit causes the relay 92 to remain closed until such time as segment 66 departs from its respective stationary contact. This action of the relay 92 is preparatory, establishing conditions to be subsequently utilized in a manner later described.

Fourth forward position of the controller

Upon movement of controller 35 from its third into its fourth forward position, segment 97 is brought into engagement with its respective stationary contact thus extending a control current circuit from lead 40 through lead 98, auxiliary contacts 89 and lead 99 to one terminal of the winding of a fourth step contactor 100. The opposite terminal of the winding of contactor 100 is joined by a lead 101 with the lead 48 thus completing a control circuit which causes contactor 100 to close further reducing the amount of resistance of the grid 58 which is included in the secondary circuit of motor 11. Closure of contactor 100 causes closure of auxiliary lock-in contacts 102 for the purpose of preparing a circuit to be subsequently utilized.

Fifth forward position of the controller

Upon movement of controller 35 from its fourth into its fifth forward position, segment 103 is brought into engagement with its respective stationary contact, establishing a control circuit extending from lead 40 through lead 104, lock-in contacts 102 and lead 105 to one terminal of the winding of a fifth step contactor 106. The opposite terminal of the winding of contactor 106 is joined by a lead 107 with lead 48 thus completing a control circuit which causes contactor 106 to close thus further reducing the amount of re-

sistance in grid 58 which is contained in the secondary circuit of motor 11. Motor 11 is thus caused to operate at its maximum speed.

Deceleration from the forward driving positions of the controller

As the controller 35 is moved from the fifth to the fourth forward position the control circuit of the fifth step contactor 106 is interrupted causing the latter to open thus increasing the resistance in the secondary circuit of motor 11. Similarly when controller 35 is moved from the fourth to the third position the control current circuit of fourth step contactor 100 is interrupted causing the latter to open, further increasing the secondary resistance of the motor 11. Thus a drifting deceleration of the bridge of the crane takes place upon shifting of the controller from its higher position.

In contrast movement of the controller 35 from the third to the second forward position causes segment 68, previously mentioned to come into engagement with its respective stationary contact thus establishing a control circuit extending from lead 40 through lead 108 to contacts 109 of decelerating relay 92 which contacts are found in closed position by reason of an action previously described. The control circuit in question then extends through lead 110 to the winding of an excitation relay 111 and thence through lead 112 to a connection with lead 48 thus completing a control circuit which causes excitation relay 111 to close.

The excitation current regulated by the relay 111 is supplied by a transformer 113 the primary of which is connected through leads 114 and 115 with leads 49 and 47 respectively. The secondary of transformer 113 is connected by leads 116 and 117 to the input terminals of a rectifier 149. Rectified excitation current is drawn from the rectifier 149 through the lead 118 which extends to the contacts of excitation relay 111 from whence it passes through lead 119 resistance element 120 and sliding contact 121 and sliding contact 122 into trolley conductor 123. Trolley conductor 123 is electrically joined in turn by lead 124 with contacts 125 of power failure relay 126. For reasons hereafter explained the contacts 125 are in closed position if power supply is being maintained and for this reason the circuit in question continues through lead 127 to the windings 128 of the induced-current brake 17. The excitation current circuit then extends from the windings 128 through lead 129 to trolley conductor 130 and thence through sliding contact 131 and lead 132 to the other output terminal of rectifier 149. Excitation current is thus supplied to the windings of eddy-current brake 17 in an amount determined by the resistance value of resistance elements 120 and 121.

Movement of the controller 35 from the third to the second position also causes segment 84 to become disengaged from its respective stationary contact thus causing third step contactor 87 to open increasing further the amount of resistance of grid 58 contained in the secondary circuit of motor 11. With power supplied to motor 11 thus further reduced in amount and with a resisting torque now being exerted by eddy-current brake 17, excited as above explained, a smooth but positive deceleration of the motor 11 and the crane driven thereby is brought about. As the rate of rotation of motor 11 decreases the resisting torque of induced-current brake 17 also decreases in well known manner while at the same time

the torque exerted by motor 11 increases. Deceleration thus continues until these opposing torques become equivalent in value whereupon the bridge 10 is propelled at a predetermined steady rate. The rate of deceleration thus is not dependent upon any special skill on the part of the operator and may be chosen so as to slow the rate of travel of the crane as rapidly as possible without causing undesirable shock or hazard.

Movement of the controller 35 from the second forward position to the first forward position, causes segment 79 to become disengaged from its respective stationary contact, thus interrupting the control circuit maintaining second step contactor 82, allowing the latter to open to cause the entire resistance value of grid 58 to become included in the secondary circuit of motor 11, thus reducing the torque which can be exerted thereby. At the same time segment 67 is brought into engagement with its respective stationary contact thus providing a control circuit extending from lead 40 through lead 133 to contacts 134 of decelerating relay 92 and thence through lead 135 to the winding of excitation relay 136 which is joined in turn through lead 137 to lead 112 and thence to lead 48. The establishment of this circuit causes excitation relay 136 to be closed which acts through lead 118 and lead 138 to shunt resistor element 120 thus increasing excitation current supplied to the eddy-current brake 17. The resisting torque exerted by brake 17 is thus enhanced while the propelling torque of motor 11 is at the same time reduced. A new equilibrium condition of lowered propelling speed for the bridge 1 is thus established and the propelling motion of the crane is smoothly reduced to a rate at which sudden application of brake 12 may thereafter take place without hazard.

Movement of controller 35 from the first forward position to the off position causes main forward contactor 28 to open terminating the supply of the propelling current to the motor 11 and terminating energization of the windings 69 and 70 of brake 12. The motion of the bridge 1 is thus brought to a complete stop.

It is to be noted that the restraining action of induced-current brake 17 is brought into play only when the controller 35 is moved from the third position into the second position and is not brought into play when the first and second positions are entered from the off position. In this way the desired decelerating effect is obtained without impairing acceleration. If for any reason it is desired that the equilibrium speed attained during acceleration in the first or second position be limited by the action of the induced-current brake 17, manually controlled switch 139 may be closed so as to cause segment 140 to supply control current through its respective stationary contact and lead 141 to the coil of the decelerating relay 92 immediately upon entering the first control position from the off position. In this way a low and steady speed of travel of the bridge 1 can be obtained, for use, for example, in the case of foundry cranes while pouring from a moving ladle or for any other service where a very low and positively regulated rate of travel is advantageous.

Reverse travel

The action of the circuit above described when the controller 35 is moved into and out of its several reverse driving positions is parallel in all respects to the action which takes place upon movement of the controller into and out of its

several forward driving positions. In this case segments 41, 142, 136, 144, 145, 37, 36 for the first reverse position, segment 84 for the second reverse position, segments 103 and 146 for the third reverse position, segment 147 for the fourth reverse position and segment 148 for the fifth reverse position, corresponding to segments 41, 66, 67, 140, 68, 36 and 37 for the first forward position, segment 79 for the second forward position, segments 90 and 84 for the third forward position, segment 97 for the fourth forward position and segment 103 for the fifth forward position come into sequential engagement with their respective stationary contacts during acceleration and deceleration so as to produce results corresponding in all respects with those described in connection with the action of the controller 35 when moved into and out of its several forward driving positions, except that the motor 11 is caused to rotate and the bridge 1 to travel in the opposite direction.

Deceleration in the event of power failure

In order to avoid the mechanical shock which would result if a power failure occurred while the bridge 1 was travelling at a speed in excess of that which could be safely arrested by brake 12 alone, the winding of power failure relay 126 is connected by leads 150 and 151 directly to the source of power supply through trolley conductors 32 and 35. Under normal conditions of operation relay 126 is held in the position shown in the drawing. Should power failure occur, however, relay 126 drops to the opposite position. Upon dropping to the lower position relay 126 through the action of its contacts 125 and 152 transfers the source of excitation current for the windings 128 of the eddy-current brake 17 from the normal source previously described to the output of an alternator 153 and rectifier 154 joined in circuit by the leads 155, 156 and 157 as shown. At the same time the output of the alternator 153 and rectifier 154 is connected by lead 158, contacts 158 and lead 159 with common lead 71 of windings 69 and 70 of brake 12. Rectifier 154 is also joined by lead 160 with lead 74 so as to supply the outer ends of windings 69 and 70 upon closure of contacts 161 of relay 126.

As long as the bridge 1 is travelling at an appreciable rate the alternator 153 through the rectifier 154 provides adequate current to maintain the brake 12 in released position, and eddy-current brake 17 is excited to cause a smooth but rapid deceleration of the bridge 1. When, but not until, the output of alternator 153 becomes insufficient to maintain brake 12 in released position the bridge 1 is brought to a stop. For the purpose of avoiding application of the brake 12 momentarily at the moment of power failure and before excitation by alternator 153 can be transferred thereto, power failure relay 126 is preferably constructed to have a quick releasing action, while brake relay 75 is chosen to have a normal opening rate. As a result contacts 161 close before the contacts of relay 75 open thus availing of the self inductance of windings 69 and 70 to maintain the brake 12 in released position until excitation supplied from alternator 153 and rectifier 154 becomes transferred thereto.

It is evident that a direct current generator or accumulator may be substituted for the alternator 153 and the rectifier 154, to produce the emergency action above described. It is preferred, however, that a self excited alternator having a permanent magnet field be employed.

since the use of brushes may be thus avoided and dependable operation secured after long years of operation without attention. This characteristic is important since normal operation of the apparatus will not reveal a derangement of this particular part, which may be called upon to act only infrequently and under conditions which are not expected. Hereafter for convenience the term generator is therefore used as meaning any suitable excitation source independent of the main power supply.

A further advantage of bridge motion energized excitation of brake 17 is that the apparatus stands ready to function whenever the crane is left unattended with power supply interrupted. In such a case if there be a derangement of the brake 12, any force tending to put the bridge into motion will be resisted so that the maximum speed which may be attained will be low enough so that stops at the ends of the runway will halt movement of the bridge 1 without damage. Where cranes are installed in the open, windstorms of unexpected severity sometimes occur and instances of very extensive damage have arisen where cranes have been put into motion by action of the wind at a time when the holding brake, such as brake 12, was not in proper functioning order. This hazard, as above explained, is avoided in apparatuses constructed in accordance with this invention by the self restraining action of the eddy-current brake 17, excited by current derived from alternator 153.

I claim:

1. In an electrically propelled apparatus having traction means, a drive system therefor comprising an electric motor; mechanical power transmitting means drivingly connecting said motor to said traction means; an induced current brake having a driven member connected to said motor in driven relationship thereto, a stationary member secured in braking relationship to said driven member, and an excitation winding for magnetizing said driving and driven members; an electric power supply circuit connected to said motor including control means adapted to be moved to and from an off position and an adjacent lower speed on zone and a more remote higher speed on zone, a preparatory decelerating relay comprising a winding for closing the same and lock-in contacts and brake energizing contacts closeable when said winding is energized, preparatory contacts closeable by said control means only on movement of the same into the higher speed on zone of the same in circuit with the winding of said preparatory decelerating relay for actuating the same to closed position, maintaining contacts closeable by said control means throughout the on zones thereof in circuit with the winding of said preparatory decelerating relay and the lock-in contacts of the same for maintaining said relay upon closure in closed position until said control means is moved to off position, braking contacts closeable by said control means only in the lower speed on zone thereof in circuit with the brake energizing contacts of said preparatory decelerating relay, and relay means having a winding connected in series with said braking contacts and said brake energizing contacts and having contacts in circuit with the excitation winding of said induced-current brake for supplying excitation current thereto when said braking contacts and said brake energizing contacts both are closed.

2. In an electrically propelled apparatus having traction means, a drive system therefor com-

prising an electric motor; mechanical power transmitting means drivingly connecting said motor to said traction means; an induced-current brake having a driven member connected to said motor in driven relationship thereto, a stationary member secured in braking relationship to said driven member, and an excitation winding for magnetizing said driving and driven members; an electric power supply circuit connected to said motor including control means adapted to be moved to and from open and closed positions to apply and interrupt the supply of power to said motor; a normal excitation supply circuit connected to the winding of said induced-current brake including control means adapted to be shifted to excite and terminate excitation of said brake; interlocking means cooperatively associated with the power control means for said motor and with the excitation current control means for said brake operative to cause said brake to be excited only on movement of said power control means for said motor from closed toward open position; and an emergency excitation source for said induced-current brake, an emergency excitation circuit joining said source and the winding of said brake, and means rendered operative upon failure of the electric power supply for said motor for causing said emergency excitation circuit to become closed.

3. The combination with an apparatus in accordance with claim 1 in which there is provided an electro-magnetically released normally set friction holding brake mounted in braking relation to said motor, a normal holding brake circuit joining said holding brake to the electric power supply for said motor operative to excite and release said brake when power is supplied to said motor, and in which the emergency excitation source includes an emergency excitation source for said holding brake and comprises a generator mechanically connected in driven relationship with said motor, a power failure relay means for said induced-current brake and said holding brake, an excitation circuit joining said holding brake and said induced-current brake to said generator through said power failure relay means, and an actuator circuit for said power failure relay means joining the same to the power supply for said motor operative upon failure of said motor power supply to cause said power failure relay means to close said emergency excitation circuit to continue excitation of said induced-current brake and to retain said holding brake in released position so long as the output of said generator is sufficient.

4. The combination with an apparatus in accordance with claim 2 in which there is provided an electro-magnetically released normally set friction holding brake mounted in braking relation to said motor, a normal holding brake circuit joining said holding brake to the electric power supply for said motor operative to excite and release said brake when power is supplied to said motor, and in which the emergency excitation source for said induced-current brake includes an emergency excitation source for said holding brake and comprises a generator mechanically connected in driven relationship with said motor, a power failure relay means for said induced-current brake and said holding brake, an excitation circuit joining said holding brake and said induced-current brake to said generator through said power failure relay means, and an actuator circuit for said power failure relay means joining the same to the power supply for

said motor operative upon failure of said motor power supply to cause said power failure relay means to close said emergency excitation circuit to continue excitation of said induced-current brake and to retain said holding brake in released position so long as the output of said generator is sufficient, said power failure relay means including contacts operative to open the normal excitation circuits of said induced-current brake and said holding brake upon closure of said emergency excitation circuit.

5. The combination with an apparatus in accordance with claim 2 in which there is provided an electro-magnetically released normally set friction holding brake mounted in braking relation to said motor, a normal holding brake circuit joining said holding brake to the electric power supply for said motor operative to excite and release said brake when power is supplied to said motor, and in which the emergency excitation source for said induced-current brake includes an emergency excitation source for said holding brake and comprises a generator mechanically connected in driven relationship with said motor, a power failure relay means for said induced-current brake and said holding brake, an excitation circuit joining said holding brake and said induced-current brake to said generator through said power failure relay means, and an actuator circuit for said power failure relay means joining the same to the power supply for said motor operative upon failure of said motor power supply to cause said power failure relay means to close said emergency excitation circuit to continue excitation of said induced-current brake and to retain said holding brake in released position so long as the output of said generator is sufficient, said power failure relay means including contacts operative to open the normal excitation circuits of said induced-current brake and said holding brake in advance of closure of said emergency excitation circuit and transfer contacts operative to shunt said holding brake to delay release of the same during the interval between the opening of the normal excitation circuit for said holding brake and the closing of said emergency excitation circuit.

6. In a driving and braking circuit for electrically propelled apparatus the combination comprising an electric propelling motor; an induced current brake having a driven member connected to said motor in driven relation thereto, a stationary member secured in braking relation to said driven member and an excitation winding for establishing a field mutual to said driving and driven members; an electric power supply circuit including a controller for said motor, said controller having an off position and positions for lower and higher speed driving of said motor; and an excitation current source for said excitation winding including switching means rendered active to complete a circuit between said excitation current source and excitation winding when said controller is in a lower speed position and said motor has been supplied theretofore with power to drive the same at a speed higher than said lower speed.

7. In a driving and braking circuit for electrically propelled apparatus the combination comprising an electric propelling motor; an induced current brake having a driven member connected

10

to said motor in driven relation thereto, a stationary member secured in braking relation to said driven member and an excitation winding for establishing a field mutual to said driving and driven members; an electric power supply circuit including a controller for said motor, said controller having an off position and a plurality of driving positions for driving said motor at different speeds; and an excitation current source for said excitation winding including switching means rendered active to complete a circuit between said excitation current source and said excitation winding when said controller is placed in one of its said driving positions having been first moved from its said off position to a predetermined activating position.

15

8. In a driving and braking circuit for electrically propelled apparatus the combination comprising an electric propelling motor; an induced current brake having a driven member connected to said motor in driven relation thereto, a stationary member secured in braking relation to said driven member and an excitation winding for establishing a field mutual to said driving and driven members; an electric power supply circuit including a controller for said motor, said controller having an off position and a plurality of driving positions for driving said motor at different speeds; and an excitation current source for said excitation winding including switching means rendered active to complete the circuit between said excitation current source and said excitation winding when said controller is placed in a predetermined driving position after first being moved through a driving position more remote from said off position.

9. In a driving and braking circuit for electrically propelled apparatus the combination comprising an electric propelling motor; an induced current brake having a driven member connected to said motor in driven relation thereto, a stationary member secured in braking relation to said driven member and an excitation winding for establishing a field mutual to said driving and driven members; an electric power supply circuit including a controller for said motor, said controller having an off position, a plurality of driving positions and a retarding position; and an excitation current source rendered active to complete a circuit between said excitation current source and said excitation winding when said controller has been moved first from its off position to one of its said driving positions and then to its said retarding position.
